UNITED STATES PATENT OFFICE

2,545,006

MEANS FOR COATING FILAMENTS

Albert Olen Ryan, Independence, Ky., assignor to Redding Manufacturing Company, Inc., Norwalk, Conn., a corporation of Delaware

Original application October 20, 1944, Serial No. 559,497. Divided and this application February 12, 1947, Serial No. 728,149

2 Claims. (Cl. 91—32)

1

This invention relates to improvements in means for coating filaments, and is more particularly directed to means for covering wires and the like with insulation, and this application is a division of my co-pending application Serial Number 559,497, filed October 20, 1944, on which U. S. Patent No. 2,456,650 was issued December 21, 1948.

An object of this invention is to provide simple and improved means for forming a continuous coating, such as insulation, about a filament, such as a wire.

Another object of this invention is to provide a means for coating wire, which assures a true centering of the wire within the coating so formed.

More specifically, my invention is directed to means whereby a stream of coating material is discharged about the filament to be coated, into a second confining stream, which in some cases may function as a hardening material, moving with streamlined flow in a restricted passage, so that as the filament, coating material, and confining material move along, the coating material gradually becomes hardened and coats the enclosed filament.

Other objects and advantages of the present invention will appear from the following description of examples thereof, illustrated in the accompanying drawings, in which:

Fig. 1 is a vertical cross-sectional view of a portion of my apparatus, with other apparatus indicated diagrammatically, of a preferred form of arrangement in accordance with the present invention;

Fig. 2 is an enlarged vertical cross-sectional view of a portion of the apparatus illustrated in Fig. 1.

The apparatus shown by way of example in the drawings may consist of a hollow cylindrical tube 10 having a relatively long section of uniform, small internal diameter throughout its length to its exit end, and a short section on one end of relatively greater internal diameter. In the form of invention shown, this tube is preferably mounted vertically, with the larger section on top. Within the larger section of the tube 10 is mounted a second hollow tube 12 having a discharge nozzle 14 arranged at that portion of the tube 10 where the latter is changing to a smaller diameter. A filament to be coated passes through an opening in the top of the smaller tube 12, passes outwardly through the nozzle 14 and then downwardly through the smaller diameter section of the tube 10, and may be guided therefrom by means such as rollers 34. The liquid carrier

2

18 for the coating material is fed into the top of the tube 10, as from a source 20, and flows downwardly through the tube. The coating material 22 is fed into the inner tube 12 and passes downwardly, outwardly through the nozzle 14 about the filament 16. A source of coating material 24 will be connected to the tube 12.

The carrier liquid 18, after passing through the lower end of the tube 10, may be collected in a sump 26 for re-use. A pump 28 may be used to return this material to the source 20 and, if the action to be described in more detail later involves the use of a heated carrier liquid, a heater 30 may be interposed between the pump 28 and the source 20.

While the filament 16, to be coated, may be generally kept under suitable tension over the rollers, if this filament is a wire it is necessary that it be maintained free of bends or kinks, and it must be suitably centered. Within the tube 12 there may, therefore, be provided centering spiders 32 to effect this result.

If it is desired to coat the filament 16 with latex, liquid latex will be used as a coating material while heated glycerine may be used as the carrying fluid. Both the latex and glycerine are fed into their respective tubes at such pressures that the discharge speed of the latex from the nozzle 14 is identical with the speed of flow of the glycerine in contact with the latex at this discharge point, and the speed of both of the materials at their interface is preferably identical with the speed of movement of the filament to be covered when the flow results from the hydraulic pressure above. The speeds are all so related to the viscosities of the materials used and the size of the filament, outer diameter of the latex and the inside diameter of the very small tube 10 to bring about a condition known as streamlined or viscous flow. Under all conditions the glycerine surrounding the latex will drag along the inner surface of the tube while at the interface of the glycerine and the latex the speed of each will be identical. When the speed of the filament is greater than the maximum speed in the latex due to hydraulic pressure, it produces a drag on the latex which will increase the rate of flow. The linear speed of the filament must be limited by conditions to insure that streamlined flow results. Under all the above conditions the glycerine will confine the latex to a definite size and shape by acting as a lubricating, mobile, confining wall and on moving downward through the tube 10, the latex will gradually become coagu-

lated about the filament, forming the coating 22' indicated in Fig. 2. The coated filament is then drawn off over the rollers 34 and subjected to any further necessary treatment, while the glycerine, discharged into the sump 26, may be pumped back for re-use.

It is to be pointed out that the invention is applicable to the coating of a wide variety of filaments with a wide variety of material. For example, the filament may be a single or multiple strand of metallic wire, a single or multiple thread of any suitable textile material, a single or multiple thread of natural or synthetic rubber, resins, plastics or fiberglass, or, in fact, any filamentary substance which can be used with a minimum of tension.

If, for example, the invention is used to coat a solid or stranded copper wire, the coating material may be emulsions or dispersions of plasticized vinyl-acetate-vinyl chloride copolymers, plasticized polystyrene, polyethylene or other mixtures. The liquid carrier in such cases will be material used to destabilize the emulsion, or to change the liquid coating into a solid coating by any suitable chemical or physical change required.

The invention is equally applicable to the coating of threads or cords with natural or synthetic rubber, natural or synthetic resin, cellulose derivatives, waxes, or any other mixtures. Likewise, the original filament may be a copper wire which may then be coated with suitable asphaltic materials, waxes, paints or lacquers.

Another use for the present invention, involving the principles outlined above, is in the formation of small hollow filaments. This merely involves the coating of a central filament with, however, a material which does not adhere to this filament. After the coating has been applied in any one of the manners described above, the core may then be removed, leaving a hollow filamentary structure.

Accordingly, while I have, for the purposes of illustration, described one particular form of apparatus for carrying out my invention, I have indicated several examples of the manner in which the principles according to this invention are applicable, it is to be understood that the invention is not limited to the examples given, but only as set forth in the objects and the claims which follow.

I claim:

1. Apparatus for coating filaments comprising, a tube having a coating hardening and shaping portion of small uniform cross section throughout its length to its exit end and having a cross sectional shape of approximately the cross sectional shape desired for the coated filament, means for continuously advancing a filament through said tube, means for flowing a coating liquid around said moving filament within said tube, and means for flowing another liquid through said tube and around said filament and its surrounding coating liquid, and means for controlling the flow rates of said coating liquid and said other liquid in relation to the cross sectional size of the tube to cause them to flow through the tube with viscous flow.

2. Apparatus for coating filaments comprising, a first tube having a portion of small uniform cross section throughout its length to its exit end and of approximately the cross sectional shape desired for the filament coating, a second tube axially aligned with said portion of said first tube and positioned to discharge into said portion of the first tube, means for advancing said filament through said second tube into and through said portion of said first tube along the longitudinal center line of said portion of said first tube, a first reservoir and a first conduit communicating with said second tube, a second reservoir and a second conduit means communicating between said second reservoir and said first tube and entering said first tube in advance of said portion of the first tube and in advance of the discharge end of said second tube, and means for controlling the flow of liquids from said reservoirs to control the pressure of said liquids at their conjunction in said first tube and to regulate the pressure differential of said liquids.
